(57) **CLAIM**

The ornamental design for a two-dimensional tag, as shown and described.

DESCRIPTION

The file of this patent contains at least one color drawing. Copies of this patent with color drawing will be provided by the Office upon request and payment of the necessary fee. FIG. 1 is a front view of a two-dimensional tag showing our new design; and,

FIG. 2 is a front view shown in an environment of use. The broken lines illustrate portions of the article that forms no part of the claimed design.
